UNITED STATES PATENT OFFICE.

GIUSEPPE VIDOLI, OF RENO, NEVADA.

SPRING-PRESS.

1,187,572.

Specification of Letters Patent. Patented June 20, 1916.

Application filed October 25, 1915. Serial No. 57,647.

To all whom it may concern:

Be it known that I, GIUSEPPE VIDOLI, a citizen of the United States, residing at Reno, in the county of Washoe and State 5 of Nevada, have invented new and useful Improvements in Spring-Presses, of which the following is a specification.

This invention relates to a spring press.

One of the objects of the present invention is to provide a simple, substantial, easily operated press for forming or bending the several leaves of which a standard elliptical spring is constructed and to provide means by which the several leaves in a 15 set may be formed in one operation.

Further objects will hereinafter appear.

The invention consists of the parts and the construction and combination of parts, as hereinafter more fully described and 20 claimed, having reference to the accompanying drawings, in which—

Figure 1 is a side elevation of the press. Fig. 2 is an end view of same. Fig. 3 is a 25 sectional view of the spring leaf holder taken on line 3—3 of Fig. 5. Fig. 4 is an end view of same. Fig. 5 is a bottom view of the holder, showing the spring leaves in position.

Referring to the drawings in detail, A 30 indicates a frame of suitable size and construction upon which is mounted a stationary forming die or anvil 2. Mounted above the die 2 in direct alinement with same and guided by means of a pair of rods 3 which pass through a pair of bearings 4, carried by the upper end of the frame, is a 35 hammer or movable die 5, which is raised and lowered with relation to the anvil 2 by means of a lever 6 which is pivotally 40 mounted, as at 7, upon the frame. This lever is connected with the hammer 5 by means of a link 8 and the lever may be locked in its raised position by means of a pawl 9, which is operated by suitable means, such 45 as the rod 10. Adapted to be raised and lowered with relation to the anvil 2 by means of a lever 11, is a platform 12 upon which are secured three pairs of guide rods, such as indicated at 13, 14 and 15. These 50 rods extend through the base plate 16 upon which the anvil is mounted and in a position where they will embrace the leaf springs and hold same in alinement with the forming die; the platform carrying the 55 guide rods may be locked or supported in

its raised position by means of the pawl and ratchet, indicated at 17.

In the manufacture of leaf springs of the standard elliptical type, a suitable number of flat blanks or leaves of different lengths are usually provided. These are first placed in the fire and heated to a desired temperature. They are then placed in a holder, indicated in Figs. 3, 4 and 5, which in turn is placed between the forming dies or the hammer and anvil in the press, and are here subjected to pressure of the blow of the hammer, to produce the desired shape or curvature.

The holder proper consists of a fork shaped frame 18 provided with a handle 19 to permit it to be conveniently handled. One of the legs of the fork-shaped frame is pivotally mounted, as at 20, while the other leg 21 is rigid and stationary. Suspended from the center portion of the fork-shaped frame or the upper bar of same by means of rods 22, is a plurality of intermediate spacing and forming dies 23, and passing through the pivotally mounted rods 22 upon which 25 the intermediate forming dies 23 are secured, is a pair of horizontally disposed rods 24, which are operated in unison to either clamp or release the spring leaves 25 placed between the intermediate spacing dies by 30 means of a lever 26. After the several leaves or blanks 25 have been brought to the desired temperature it is necessary to insert the leaves between the intermediate spacing dies 23. The spacing dies are then 35 separated by swinging the lever 26 into the dotted line position, indicated at 26^a. They are furthermore separated by coil-springs 27 which are carried by the rods 24 and interposed between each set of suspension rods 22. 40 After the intermediate dies have been separated by the operation, as described, it is then possible to insert the leaves or blanks 25 between the dies, as indicated in Figs. 3 and 5. The lever 26 is then brought back to the full-line position shown, and this movement of the lever pulls the rods 24 in the direction of arrow *a* and causes sufficient compression of the springs 27 to bring the intermediate dies together and clamp 45 the blanks between same.

The holder as a unit containing the leaf blanks is then placed on the anvil 2; the platform 12 is then raised into a position where the guide rods 13 will straddle the 50

leaf springs supported in the holder, thus insuring a perfect alinement of same upon the anvil. The hammer 5 or upper die 5 is then depressed and sufficient pressure is brought to bear upon the same to bend the several leaves into the desired shape; said shape being determined by the shape of the anvil and hammer, and also by the intermediate spacing dies 23. The dies are retained in the depressed position by means of a weight 30 and the lever may remain in this position until the several leaves of the spring have cooled sufficiently to retain the shape or permanent set required.

15 It will be observed that during the descent of the die 5, it first acts upon the outer ends of the long blanks and then successively and quickly upon the ends of the shorter blanks. The pressure applied or power required is thus gradually transmitted, as each leaf is bent to set in successive order.

20 The provision of the intermediate spacing dies 23 permits each leaf to be bent to assume a different curvature and it also permits all the leaves comprising a set to be formed in one operation. A uniform product is furthermore produced and a great saving in cost of manufacture is secured, as the time required is greatly decreased by the 30 present operation.

25 After the leaves have been set or given their proper respective curvature, it is only necessary to raise the hammer 5, remove the holder 18 and release the several leaves by 35 moving the lever 26 into the dotted line position, shown. The same cycle of operation takes place with each set of springs and any suitable form of tongs may be provided for the purpose of placing the leaves in the 40 holder and as this forms no part of the present invention, no means have been illustrated.

45 The materials and finish of the several parts of the device may be such as the judgment and experience of the manufacturer may dictate.

50 I wish it understood that various changes in form, proportions and minor details of construction may be resorted to within the scope of the appended claims and that I do not wish to limit myself to the specific design and construction here shown.

Having thus described my invention, what 55 I claim and desire to secure by Letters Patent is—

60 1. A spring press comprising a frame, a stationary die on the frame, a movable die reciprocally mounted above and in alinement with the stationary die, means movable to and from a position alongside of the stationary die for supporting a plurality of leaves in alinement with and on the stationary die, and means for reciprocating the movable die.

65 2. A spring press comprising a stationary

die, a coöperable die movable relative thereto, and a holder insertible between the dies and consisting of a body, and a plurality of intermediate dies pivotally mounted on the body and projecting therefrom to lie between the first dies with the body free thereof.

70 3. A spring press comprising a frame, a stationary die on the frame, a movable die reciprocally mounted above and in alinement 75 with the stationary die, intermediate dies between which spring leaves are insertible, means for retaining the insertible dies and leaves in alinement with the stationary die, said retaining means being movable to and from a position in which they project from the stationary die on opposite sides, and means for depressing the movable die with sufficient pressure to bend the leaves.

80 4. A spring press comprising a frame, a stationary die on the frame, a movable die reciprocally mounted above and in alinement 85 with the stationary die, intermediate dies between which spring leaves are insertible, means for reciprocating the movable die, and means for retaining the intermediate dies and leaves in alinement with the stationary die, said means comprising a platform 90 mounted below the stationary die, a plurality of guide pins secured on the platform and straddling the die, and means for raising and lowering the platform.

95 5. A spring press comprising a frame, a stationary die on the frame, a movable die reciprocally mounted above and in alinement 100 with the stationary die, intermediate dies between which spring leaves are insertible, means for reciprocating the movable die, means for retaining the intermediate dies and leaves in alinement with the stationary 105 die, said means comprising a platform mounted below the stationary die, a plurality of guide pins secured on the platform and straddling the die, means for raising and lowering the platform, means for supporting the platform in its lowered position and means for supporting the platform in the raised position.

110 6. The combination with a stationary and a movable die, of a spring leaf holder insertible between same, a plurality of intermediate dies between which spring leaves are arranged pivotally supported in the holder, resilient means for automatically separating the intermediate dies, and means 115 for drawing said dies together to clamp the leaves between same.

120 7. A spring press comprising a stationary die, a coöperable die movable relative thereto, and a holder insertible between the dies 125 and consisting of a forked body, a plurality of intermediate dies pivoted in the fork of the body and extending therefrom to permit of the last dies being interposed alone between the first dies, and means on the 130

body to hold the intermediate dies rigidly related.

8. A spring press comprising a stationary die, a coöperable die movable relative thereto, and a holder insertible between the dies and consisting of a forked body, a plurality of intermediate dies pivoted in the fork of the body and extending therefrom to permit of the last dies being interposed alone between the first dies, spring means tending

to hold the intermediate dies apart, and means on the body to clamp the last dies together.

In testimony whereof I have hereunto set my hand in the presence of two subscribing 15 witnesses.

GIUSEPPE VIDOLI.
